UNITED STATES PATENT OFFICE.

CHARLES A. NYE, OF MINNEAPOLIS, MINNESOTA.

FUMIGATING APPARATUS.

1,031,145.

Specification of Letters Patent.

Patented July 2, 1912.

Application filed July 24, 1911. Serial No. 640,050.

To all whom it may concern:

Be it known that I, CHARLES A. NYE, a citizen of the United States, residing at Minneapolis, in the county of Hennepin and State of Minnesota, have invented certain new and useful Improvements in Fumigating Apparatus; and I do hereby declare the following to be a full, clear, and exact description of the invention, such as will enable others skilled in the art to which it appertains to make and use the same.

My invention has for its particular object to provide an extremely simple and highly efficient fumigating apparatus, which, nevertheless, is capable of general use to vaporize and diffuse various materials such as disinfectants, deodorants, perfumes, or even for vaporizing water to maintain the proper humidity of the air in a room.

Generally stated, the invention consists of the novel devices and combinations of devices hereinafter described and defined in the claim.

In the accompanying drawings which illustrate the invention, like characters indicate like parts throughout the several views.

Referring to the drawings, Figure 1 is a side elevation of the complete vaporizing apparatus; Fig. 2 is a plan view showing the base portion of the apparatus, some parts being broken away; Fig. 3 is a horizontal section taken on the line $x^3 x^3$ of Fig. 1; and Fig. 4 is a vertical section taken approximately on the line $x^4 x^4$ of Fig. 3, some parts being shown in full.

The numeral 1 indicates, as an entirety, a small electric fan of the usual or any suitable construction, and which is shown as supported on a base plate 2, having at one side a horizontally extended arm 3. The base 2, as shown, is placed upon a shelf or table 4. The arm 3, as shown, is in the form of a yoke and is provided with an extensible section 5, the threaded stem, of which, is screwed through the outer end of said arm 3, and rigidly but adjustably held thereto by a lock nut 6.

The vaporizing receptacle is a triangular structure, the three vertical sides of which are preferably formed by light sheet metal frames 7 having perforate or reticulate

panels 8. The bottom of this vaporizing receptacle is imperforate, while the top 55 thereof, is preferably a perforated double walled triangular member 9, which normally rests loosely upon stop flanges 10 secured to the upper portions of the side frames 7.

Fitting loosely within the so-called vaporizing receptacle is a triangular liquid containing tank 11. Evaporating wicks 12 have their lower ends immersed in the liquid 60 contained in the tank 11, and to hold the said wicks in an upright position exposed to the blast from the fan, they are passed through the perforated upper portion of a skeleton-like supporting rack 13 secured on the top of the tank 11. The numeral 14 65 indicates a filling pipe that extends upward from one corner of the tank 11 so that the latter may be filled without removing the tank from the vaporizing receptacle.

The bottom plate of the vaporizing receptacle is detachably seated on a supporting head 15 which, as shown, is T-shaped, and is provided with three angular pockets 16 that engage with the three corners of the vaporizing receptacle. This supporting 70 head 15 is shown as provided with a threaded stem 17 that works with threaded engagement through the head of the arm extension 5, and is adjustably locked thereto by a lock nut 18.

As is evident, the liquid disinfectant, deodorant, or other material will be absorbed by the wick 12 and will be evaporated directly in front of the blast from the fan. The blast from the fan will be partly deflected by the 75 diverging sides of the vaporizing receptacle, but a very great part of the blast will be forced through the perforations of the panels and will be very thoroughly and directly commingled with the vapor from 80 the wicks, and furthermore, by direct action on the wicks will produce a very rapid evaporation of the liquid, which, being taken up by the air, will be thoroughly diffused and absorbed by the air.

The supporting arm 3, as shown, is slanged and detachably secured to a base 2 by small nutted bolts 19, but in some instances, it may be desirable to secure the said arm directly to a wall or other support.

The device, as is indicated, is especially

intended for use as a disinfectant or de-
odorizing apparatus, but is capable of very
wide range of use as a vaporizer.

What I claim is:

5 The combination with a fan, of a vapor-
izing receptacle having perforated walls ex-
posed to the blast of said fan and diverg-
ing therefrom, a liquid tank within said re-
ceptacle, a wick supporting rack on said

tank, and wicks extending from said tank 10
and exposed to the blast of said fan, sub-
stantially as described.

In testimony whereof I affix my signa-
ture in presence of two witnesses.

CHARLES A. NYE.
